(57) **CLAIM**

The ornamental design for a replacement spring action roller, as shown and described.

DESCRIPTION

FIG. 1 is a top view of replacement spring action roller showing my new design

FIG. 2 is a front view of a replacement spring action roller showing my new design

FIG. 3 is a left side of a replacement spring action roller showing my new design

FIG. 4 is a right side view of a replacement spring action roller showing my new design

FIG. 5 is a front perspective view of a replacement spring action roller showing my new design

FIG. 6 is a left side perspective view of a replacement spring action roller showing my new design

FIG. 7 is a front perspective view of a second embodiment of replacement spring action roller showing my new design

FIG. 8 is a left side perspective view of a second embodiment of replacement spring action roller showing my new design

FIG. 9 is a front perspective view of a third embodiment of replacement spring action roller showing my new design; and,

FIG. 10 is a left side perspective view of a third embodiment of replacement spring action roller showing my new design.

My new replacement spring action roller is characterized by having shaped annex embodiment added to one side, which is pushed with fingers during the spring action procedure.
